[57] CLAIM

The ornamental design for a combined word processor and computer, as shown and described.

DESCRIPTION

FIG. 1 is a top, front and right side perspective view of a word processor having a function as an electronic computer showing our new design,
FIG. 2 is a front elevational view thereof,
FIG. 3 is a rear elevational view thereof,
FIG. 4 is a top plan view thereof,
FIG. 5 is a bottom plan view thereof,
FIG. 6 is a left side elevational view thereof,
FIG. 7 is a top, front and right side perspective view thereof, the display panel in raised position, the printer cover in opened position and the carrying handle in extended position. The floppy disk is shown in broken lines for illustrative purposes only and forms no part of the claimed design.
